UNITED STATES PATENT OFFICE

DEAN J. PEAKER AND FRANK H. LONGFELLOW, OF MACKSBURG, OHIO.

CHECK PROTECTOR

Application filed July 26, 1930. Serial No. 471,006.

This invention relates to improvements in devices for preventing the alteration of names or amounts on checks or other valuable papers.

The primary object of the present invention is to provide a small paper perforating device of neat and novel construction by means of which the amount of a check, either the written or printed amount, may be protected from alteration by perforating the portion of the paper where the amounts are inserted.

Another object of the invention is to provide a pocket check protector having a guard over the perforating rolls to prevent damage to the rolls by the accidental engagement of the same with portions of the clothing and also to prevent damage to the clothing of the person carrying the device.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a top plan view of the check protecting device embodying the present invention.

Figure 2 is a longitudinal sectional view of the device.

Figure 3 is a view in transverse section taken on the line 3—3 of Figure 2.

Figure 4 is an elevational view of the front end of the device.

Figure 5 is an elevational view of one side of the device at the front end, parts thereof being broken away.

Referring more particularly to the drawings wherein like numerals of reference indicate corresponding parts throughout the several views, the numeral 1 indicates generally the casing of the present protector which comprises a top and bottom portion 2

and 3 respectively connected at one end by the rounded wall portion 4. As shown the top and bottom of the casing, which portions may be termed the jaws thereof, are relatively long and are formed integral with the rear portion 4 which portion may be tempered, if the casing is to be of metal construction so that the forward ends of the jaw portions may be maintained in spaced relation.

Each of the jaws has a side wall 5 formed integral therewith which side walls extend from the forward ends of the jaws to a point adjacent the resilient connecting portion 4, the opposed edges of the walls carried by the upper and lower jaws being normally spaced apart in the manner shown through the resilient action of the portion 4 which connects the jaws.

At the forward end of the protector there is formed adjacent and in connection with each side wall of each jaw a front wall portion 6 and the top edge of the top jaw 2 is provided between the adjacent wall portions 6 with an upstanding rib 7.

Upon the inner faces of the walls 5 carried by the upper and lower jaws of the device there are formed the opposed bearings 8. Disposed between the walls 5 of the upper jaw and the two walls of the lower jaw are rollers 9, the peripheral faces of which are serrated or toothed as indicated at 10 and at each end of each of these rollers is a trunnion 11 which is mounted in an adjacent bearing 8. These rollers are also normally spaced apart and when the jaws are forcibly moved together against the tension of the connecting portion 4 therebetween the serrations or points upon the peripheries of the rollers intermesh so that if a check or other sheet of paper is interposed therebetween indentations or perforations will be formed therein and these may be made to cover a strip of the paper by drawing the same lengthwise of the protector device between the engaged rollers.

Extending transversely of the lower jaw in front of the rollers 9 and below the one carried by the lower jaw is a shaft 12 upon which is mounted a door 13, the mounting being accomplished through the medium of a pair of ears 14 carried thereby, through

which the shaft 12 passes. The shaft 12 is surrounded by a coiled spring 15, one end of which is held by the adjacent jaw 3 or an adjacent wall thereof while the other end bears against the door 13 in the manner shown and this spring is so formed that it constantly acts to force the door to open position. When the door 13 is swung upwardly upon the shaft 12 it completely closes the space between the upper and lower front wall portions 6 and between the forward edges of the upper and lower jaws 2 and 3 and in order to maintain the door in closed position against the tension of the spring the forward edge thereof is provided with a lip 16 which frictionally engages over the rib 7 upon the top jaw. Since it is necessary to slightly compress the jaws in order to force the lip 16 over the rib 7 it will be readily seen that the normal tendency of the jaws to separate and maintain the desired engagement between the lip and the rib will thus keep the door 13 in closed position. In order to open the door it is only necessary to move the jaws 25 of the device together whereupon the lip 16 will be released and the spring 15 will act to throw the door open to the position shown.

A check or other paper may then be entered between the rollers 9 and moved inwardly the full length of the protector and by then compressing the jaws to force the rollers together until the paper is gripped thereby, and then drawing the paper outwardly it will be readily seen that a perforated strip will be formed in the paper of a width equal to the width of the rollers 9 and of a length substantially equal to the length of the jaw members.

Since the present device as designed may be made relatively small the portion 4 thereof may be provided with an eye or ring 17 so that the device may be conveniently attached to a watch chain or to a key ring as desired.

Having thus described our invention, what we claim is:

1. A check protecting device, comprising an elongated casing having a top and bottom wall, said walls being joined at one end by a resilient connecting wall, a side wall carried by and extending inwardly from the longitudinal edge of said top and bottom walls, the free edges of the side walls of the top of the casing being in spaced opposed relation to the adjacent edges of the other side walls, a pair of perforating rollers each being rotatably mounted between a pair of side walls, said rollers being designed to be brought into contacting relation, and a removable front wall for the casing at the end opposite said resilient wall.

2. A check protecting device, comprising an elongated casing having a top and bottom wall, said walls being joined at one end by a resilient connecting wall, a side wall carried by and extending inwardly from the longi-

tudinal edge of said top and bottom walls, the free edges of the side walls of the top of the casing being in spaced opposed relation to the adjacent edges of the other side walls, a pair of perforating rollers each being 70 rotatably mounted between a pair of side walls, said rollers being designed to be brought into contacting relation, a shaft extending transversely between a pair of side walls at the other end of the casing from said resilient portion, a door for closing said other end of the casing mounted upon said shaft, and resilient means mounted on the shaft and engaging the door and normally urging the same to open position. 75

3. A check protecting device, comprising an elongated body having a top and bottom wall connected at one end by a resilient rounded wall, each of said top and bottom walls having a longitudinally extending side wall, 80 the side walls of the top and bottom walls being normally in edge opposed relation, a pair of perforating rollers mounted between said top and bottom walls and arranged to be brought into contacting relation, each of 85 said rollers being rotatably supported between a pair of side walls, a door for covering the other end of the body, a shaft mounted between a pair of side walls at said other end and having said door pivotally supported 90 thereon, a spring member mounted upon said shaft and normally urging said door to open position, and catch means for maintaining said door closed. 95

In testimony whereof we hereunto affix our signatures.

DEAN J. PEAKER.
FRANK H. LONGFELLOW.
